DISPENSER FOR PRODUCTS PACKAGED IN
COLLAPSIBLE TUBES

Roland A. Merullo, Revere, Mass.

Application March 24, 1948, Serial No. 16,818

9 Claims. (Cl. 222—103)

1

My present invention relates to dispensers for products packaged in collapsible tubes having outlet tips closed by caps threaded thereon.

Such tubes are, in general, a convenient way of packaging various products of which tooth paste is perhaps the best example. The objections to their use are that the caps are frequently lost or are not replaced with the result that some of the contents deteriorate and is wasted, that when a tube is squeezed to expel its contents, more than is needed is commonly discharged, and that the average user does not fully exhaust the contents of the tube before it is discarded.

In accordance with my invention, I provide a dispenser for products packaged in such collapsible tubes that consists of a housing having a tube receiving chamber open at one end and provided with means to exert a collapsing pressure on a tube in that chamber thereby to expel its contents through its threaded outlet tip. Connected to the housing adjacent the open end of the chamber is a support to which is attached a gate for movement relative thereto between open and closed positions. I provide a member adapted to be connected to the tip of the tube and that member is held by the support to maintain it in operation relative to the gate. I prefer that the member be movable relative to its support in a direction transversely of the tube axis so that the tip may move along a pathway under the influence of the tube collapsing means thereby to ensure that the tube contents may be more completely exhausted than is the case if the tube tip is rigidly held. This is also necessary to enable different sized tubes to be used efficiently in the same dispenser and to ensure that they are properly positioned therein. For that reason, the aperture in the gate through which the tube contents flow in the open position of the gate is in the form of a slot so that the tip may register therewith in any of its positions along its pathway.

In the drawings I have shown an illustrative embodiment of my invention from which these and other of its novel features and advantages will be readily apparent.

In the drawings:

Fig. 1 is a side view of a dispenser in accordance with my invention.

Fig. 2 is a longitudinal section through the dispenser of Fig. 1.

Fig. 3 shows the dispenser in front view, and

Fig. 4 is a section along the lines 4—4 of Fig. 2.

As illustrative of my invention, I have shown

2

a dispenser particularly adapted for use with tooth paste packaged in a collapsible tube 10 having a threaded outlet tip 11.

The dispenser shown in the drawings consists of a housing 12 having an open-ended chamber 13 and a back wall 14 with reference to which the housing 12 is so located that end portions 15 and 16 of the back wall are exposed for convenience in attaching the dispenser to any suitable supporting surface. The front portion 15 is preferably so shaped, as indicated in Fig. 1, that it is concealed by the detachable closure, generally indicated at 17, for the open end of the chamber 13 and has a single countersunk hole 18 to receive an attaching screw. The rear portion 16 is shown as of substantial length and is divided by a horizontal rib 19 spaced an equal distance from the top and bottom edges thereof and extending across the rear end of the housing 12. I provide the rib 19 with a plurality of apertures 20 dimensioned to receive tooth brush handles and on each side of it is a countersunk hole 18 for other attaching means.

While the tube collapsing means may be of any type, I have shown such as comprising a pressure plate 21 within the chamber 13 and of substantially the same length as the largest tube that may be used in the dispenser. The plate 21 has a bearing 22 engageable by the handled stem 23 threaded through the housing 12 so that as it is rotated in one direction or the other, the plate 21 is forced into or out of contact with the tube 10. Preferably, the stem 23 is parallel to the back wall 14 of the dispenser.

The dispenser may be attached to a suitable supporting surface with the stem 23 in an upright or in a depending position and it is proportioned to be equally attractive and equally serviceable in either position as may be desired by preference or required by the location of the wash bowl, cabinet or other fixtures.

The closure 17 consists of a first annular shell 24 secured at one end to the housing 12 as by a bayonet joint indicated at 25 and having, at its other end, an inwardly disposed annular flange 26 to which a second annular shell, generally indicated at 27, is secured by bolts 28 having their heads concealed by the first shell 24. The second shell 27 has an outlet port 29 and establishes a chamber 30 in which I mount an element 31 for movement relative thereto transversely of the outlet port 29 and having an aperture threaded to receive the tip 11 of the tube 10. I pivotally mount a gate 32 within the chamber 30 and having an actuating arm 33 extending through a slot

34 in the periphery of the second shell 21 so that it may be moved from a first or closed position into a second or open position.

In practice, the second shell consists, as may be best seen in Fig. 2, of a disc 35, an end wall 36, and a ring 37 which constitutes a spacer so that the length of the chamber 30 is such as to accommodate the gate 32 and the element 31 for which the disc 35 constitutes a seat as it moves relative thereto and maintains it in contact with the gate 32. Preferably, the inner edges of the disc 35 and the flange 26 are beveled and dimensioned so that together they define a tapered port for the chamber 30 having its larger end disposed towards the chamber 13 and the outlet port 29 is oppositely tapered.

In the illustrative embodiment of my invention shown in the drawings, the gate 32 is pivotally supported as at 38 between the spacer 37 and the end wall 36 and the adjacent faces of the end wall 36 and the spacer 37 are formed with complementary marginal shoulders 39 of sufficient length to define a major arc so that on assembly, the peripheral slot 34 is established. The bolts 28 extend freely through the disc 35 and the shoulder 39 of the spacer 37 and are threaded into the shoulder 39 of the end wall 36. As such adjacent faces are similar, I have shown only that of the spacer 37 which may be seen in Fig. 4.

As will be apparent from Fig. 4, the gate 32 in its closed position has its actuating arm 33 yieldably seated against one end of the slot 34 by the spring 40 attached at one end to the gate 32 and at its other end to the spacer 37.

As a dispenser in accordance with my invention is used, the tube collapsing means are actuated to exert pressure on the tube 10 to expel its contents through its tip 11 normally blocked by the gate 32. As the tube 10 is collapsed further, the tip 11 is free to move in the direction of the pressure applied to the tube since it is attached to the element 31 which is movable relative to the second shell. This ensures that the tube contents may be much more completely exhausted than would be the case if the tip were rigidly secured to the closure 18.

For that reason, the port 41 in the gate 32, which in the second position of the gate effects communication between the tube tip 11 and the outlet port 29, is in the form of a slot which registers in that second position with any position of the tip 11 as it moves along a pathway under the influence of the tube collapsing means.

In use, the closure 17 is removed as a unit and the tip 11 is screwed into the element 31. The tube 10 is then inserted into the chamber 13 so that its end 42 is in parallel with the pressure plate 21 and the closure 17 is replaced. Because of the fact that the element 31 is movable relative to the closure 17, the position of the tube will not be affected by the attachment of the closure 17 to the housing 12 and this same fact ensures proper operation even if the tube 10 is not inserted properly into the chamber 13. The handled stem 23 is then rotated to bring the pressure plate 21 into contact with the tube 10 to exert sufficient pressure thereon to cause some of its contents to be expelled when the gate 32 is moved by the user into its open position. While with a smaller tube it is necessary to rotate the stem 23 to a greater extent, its tip 11 is properly positioned because of the fact that the element 31 is movable relative to the closure 17.

Once a tube 10 is thus attached to a dispenser

in accordance with my invention, it is only necessary for the user to move the gate 31 into its open position and the tube contents will flow out for his use until he releases the gate 31 so that it may be closed by the spring 40. With the tube collapsing means shown in the drawings, it is, of course, necessary for the user to turn the stem 23 from time to time to maintain pressure on the tube 10. When the tube 10 is emptied, the closure 17 is removed and the flattened tube 10 is then detached from the element 31. Before a new tube is attached, the closure 17 may be rinsed in hot water to clean it.

From the foregoing, it will be apparent that dispensers in accordance with my invention are of simple construction and adapted to enable products packaged in collapsible tubes to be used with increased convenience and economy.

What I therefore claim and desire to secure by Letters Patent is:

1. A dispenser for tooth paste, shaving cream, or a like product packaged in a collapsible tube having a threaded outlet tip, said dispenser comprising a housing having a tube receiving chamber open at one end, means operable by the user and attached to said housing to exert collapsing pressure on a tube in said chamber, and means to close the open end of said chamber, said means including a support connected to said housing

20 adjacent the open end of said chamber, a member having a threaded aperture for attachment to said tip end and a connection between said member and said support to enable said member to move transversely relative thereto to enable said tip to move along a pathway as its tube is collapsed by said means, and a gate to move relative to said member between a first position in which it blocks the flow of tube contents into a second position in which said flow is unblocked.

35 2. The dispenser of claim 1 in which the member and support are rotatable relative to each other.

3. A dispenser for tooth paste, shaving cream or a like product packaged in a collapsible tube 45 having a threaded outlet tip, said dispenser comprising a housing having a tube receiving chamber open at one end, means operable by the user and attached to said housing to exert a collapsing pressure on a tube in said chamber, a closure for

50 the open end of said chamber detachably connected to said housing, said closure including an end wall having an outlet port, a member having an aperture threaded for attachment to said tip and being slidably supported by said closure for

55 movement relative thereto to enable said tip to move along a pathway as its tube is collapsed by said means, and a gate supported by said closure for movement relative to said member between a first position in which it blocks the flow of tube

60 contents through said outlet port and a second position and having a slot which in said second position registers with any position of said tip along its pathway, and said outlet port being dimensioned so that the entire length of said slot

65 is in communication therewith in the second position of said gate.

4. A dispenser for tooth paste, shaving cream, or like products packaged in a collapsible tube having a threaded outlet tip, said dispenser comprising a housing having a tube receiving chamber open at one end, means operable by the user and attached to said housing to exert a collapsing pressure on a tube in said chamber, and a closure for the open end of said chamber, said closure

75 comprising a first shell detachably connected to

said housing and including an inwardly disposed annular flange, a second shell secured to said flange and including an end wall having an outlet port and spaced from said flange to establish a chamber, a member within said chamber and having a threaded aperture for attachment to said tip and being dimensioned so that it is movable transversely a predetermined distance relative to said end wall to enable said tip to move along a pathway as its tube is collapsed by said means, and a gate including an operating arm, said gate being pivotally mounted in said second shell to swing from a first position in which the flow of tube contents through said port is blocked into a second position and having a slot which in said second position registers with said outlet and with said tip in any of its positions along said pathway, and said second shell having a slot through which said gate operating arm extends.

5. The dispenser of claim 4 and bolts extending through the flange of the first shell are threaded into the second shell to provide a concealed connection therebetween.

6. A dispenser for tooth paste, shaving cream, or like product packaged in a collapsible tube having a threaded outlet tip, said dispenser comprising a housing having a tube receiving chamber open at one end, means operable by the user and attached to said housing to exert collapsing pressure on a tube in said chamber, a closure for the open end of said chamber detachably connected to said housing, said closure having an outlet port, and including a member having a threaded passage into which the tip of the tube is to be threaded, means connecting said member to said closure for movement transversely of said port as said tube is collapsed and a gate disposed between said outlet port and said member and operable by the user between open and closed positions.

7. A dispenser for tooth paste, shaving cream or like products packaged in a collapsible tube having a threaded outlet tip, said dispenser comprising a housing having a tube receiving chamber open at one end, means operable by the user and attached to said housing to exert a collapsing

pressure on a tube in said chamber, and a closure for the open end of said chamber, said closure comprising a first shell detachably connected to said housing and including an inwardly disposed annular flange, a second shell connected to said flange and comprising a disc, an end wall having an outlet port and a spacer between said disc and end wall establishing a chamber, a member in said chamber having a passage therethrough threaded for attachment to said tip and retained in said chamber by said disc but movable relative thereto to enable said tip to move along a pathway under the influence of said collapsing means, and a gate pivotally mounted in said chamber for movement between a first position in which the flow of tube contents through said outlet port is blocked and a second position and having a slot which in said second position effects communication between said tip and said outlet port in any position of said tip along said pathway, said second shell having a slot in its periphery and said gate including an arm extending outwardly through said peripheral slot.

8. The dispenser of claim 7 in which the gate is pivotally connected between the spacer and the end wall of the second shell and the adjacent faces of the spacer and end wall have marginal ribs engageable on assembly to establish the peripheral slot.

9. The dispenser of claim 7 in which bolts extend through the flange of the first shell, the disc, and spacer and are threaded into the end wall.

ROLAND A. MERULLO.
